Primary Examiner — Abraham Bahta*(74) Attorney, Agent, or Firm* — Dinsmore & Shohl LLP(57) **CLAIM**

The ornamental design for a detergent pouch, as shown and described.

DESCRIPTION

FIG. 1 is a perspective view of the detergent pouch with compartments showing my new design;

FIG. 2 is a side view thereof;

FIG. 3 is an end view thereof;

FIG. 4 is a top view thereof; and,

FIG. 5 is a bottom view thereof.

The broken line showing of portions of the detergent pouch is included for the purpose of illustrating environmental structure and forms no part of the claimed design.
